United States Patent Office

Des. 206,056
Patented Oct. 25, 1966

206,056

PULL OR THE LIKE

Dagfinn O. Amdal, Rockford, Ill., assignor to National Lock Co., Rockford, Ill., a corporation of Delaware

Filed Feb. 17, 1966, Ser. No. 1,083

Term of patent 14 years

(Cl. D10—8)

FIG. 1.

FIG. 2.

FIG. 3.

FIG. 4.

FIG. 5.

FIG. 2 is a bottom plan view thereof;

FIG. 3 is a rear elevational view thereof;

FIG. 4 is an end elevational view thereof; and

FIG. 5 is a cross sectional view thereof taken on the line 5—5 of FIG. 2.

I claim:

The ornamental design for a pull or the like, substantially as shown.
